his ATTORNEY

UNITED STATES PATENT OFFICE

RICHARD STRINDBERG, OF BRADFORD, PENNSYLVANIA, ASSIGNOR TO ANDERS JORDAHL, OF NEW YORK, N. Y.

SAFETY DEVICE FOR FUEL TANKS

Application filed July 5, 1927. Serial No. 203,335.

This invention relates to safety devices for fuel tanks, and has for its primary object and purpose to provide a fuel inlet attachment more particularly designed for use in connection with the gasoline supply tank of a motor vehicle which will preclude the possibility of the accidental dropping of a match or flame into the tank and thereby obviating the explosion thereof.

10. It is also another object of my invention to provide the inlet bushing or nipple with means for positioning the fuel supply nozzle disposed therein in spaced relation to the wall of said bushing whereby the free escape of

15. air from the tank is permitted.

More particularly, in one practical embodiment of my invention, the inwardly projecting portion of the bushing which is of sheet metal has spaced portions of its wall projected inwardly, thereby forming openings through said wall and providing a plurality of tongues or lugs thereon which serve to space the end of the supply nozzle from the wall of the bushing. An elongated screen 25 cylinder surrounds the bushing wall and extends over the openings therein, said cylinder effectually preventing the passage of the match or flame inwardly through said openings while permitting of the free egress of air 30 therethrough from the interior of the tank.

It is also a further general object of my invention to provide a device for the above purpose which may be readily applied to the ordinary fuel tank without necessitating any 35 structural alterations therein and which is of such simple construction that it may be produced at very low manufacturing cost.

With the above and other objects in view, the invention consists in the improved safety 40 device for fuel tanks and in the form, construction and relative arrangement of its several parts as will be hereinafter more fully described, illustrated in the accompanying drawings, and subsequently incorporated in the subjoined claims.

In the drawings, wherein I have disclosed one simple and practical embodiment of my present improvements, and in which similar reference characters designate corresponding 45 parts throughout the several views,

Figure 1 is a vertical sectional view showing the device applied to the wall of a fuel tank;

Fig. 2 is a top plan view, the fuel supply nozzle being indicated in dotted lines, and

Fig. 3 is a horizontal section taken substantially on the line 3—3 of Fig. 1.

In the drawing, for purposes of illustration, I have shown a section of the top wall T of a fuel tank, such for instance as is commonly provided upon motor vehicles, said tank wall having an opening t of proper predetermined diameter to receive the fuel inlet bushing or nipple. As herein shown, the fuel inlet bushing is formed from sheet metal of the required gauge or thickness and includes a body wall section 5 of such external diameter that it may be snugly fitted through the opening t in the tank wall. At the outer end of the bushing, this body wall section is provided with a laterally extending annular flange 6 which is preferably slightly inclined from a 90° angle with respect to the axis of the bushing so that only the outer edge portion of said flange has bearing contact 70 upon the outer surface of the tank wall T to which said edge portion of the flange is permanently attached or fixed, preferably by welding or a suitable solder. At the junction of the flange 6 with the body wall section 5, an annular bead 7 is formed in the metal sheet providing a convex seating surface for a suitable packing gasket indicated at G which is carried by the standard closure plug P. The section 5 of the bushing wall is internally formed with suitable threads indicated at 8 to receive this closure plug.

The bushing also includes an inner end section 9 of relatively small diameter concentrically related with the section 5 and integrally connected therewith by the annular portion 10.

The section 9 of the bushing is provided in its wall at a plurality of circumferentially spaced points with the longitudinally elongated openings 11, preferably formed by punching the metal sheet inwardly, thereby producing the internally projecting flange or lug 12 at one edge of each of these openings. In spaced relation to the openings 11 and be-

tween the same and the free end edge of the bushing section 9, the wall thereof is pressed inwardly to provide an external annular groove 13, the purpose of which will be presently explained.

To the end section 9 of the bushing above described, one end of a foraminous cylinder 14 is adapted to be attached. As herein shown, this cylinder may conveniently consist of relatively thin perforated sheet metal forming an elongated screen cylinder, one end of which is closed by a similarly perforated plate 15. At its other or open end, a flanged ring 16 is preferably secured to the outer side of the cylinder wall. In longitudinally spaced relation from this ring, the cylinder wall is provided with an internal annular bead 17.

Before applying the filling bushing and securing the same to the wall of the tank, the reduced end portion 9 of the bushing is fitted within the open end of the screen cylinder 14, the internal diameter of which is such as to provide a close frictional fit of the cylinder wall upon the external surface of the bushing wall. As the end of the bushing strikes the internal bead 17 on the cylinder wall, the cylinder wall is slightly expanded until said bead finally snaps into the external annular groove 13 of the bushing wall, and the flange of the ring 16 comes into abutting contact with the under side of the annular portion 10 of the bushing. Thus the screen cylinder is securely locked in connection with the bushing and with the wall of said cylinder extending over the several openings 11 in the wall of the bushing section 9. The perforations in the screen cylinder wall are of such size that it is not possible for a lighted match or other flame to pass inwardly through said perforations, thus precluding the possibility of the ignition and explosion of the contents of the tank from this cause.

After the bushing and the screen cylinder have been connected and the bushing secured to the wall of the tank within the opening thereof as above explained, the outer open end of the bushing is tightly closed by means of the plug P. When it is desired to replenish the tank with fuel, the plug P is unscrewed and removed, and the end of the supply nozzle on the flexible hose or tube such as is commonly seen at gasoline filling stations is inserted within the bushing. The inwardly projecting tongues or flanges 12 on the bushing wall are of such width that the tapered end of the supply nozzle may be fitted between the same until the nozzle wall rests upon the upper ends of said flanges. Thus, it will be readily seen from reference to Fig. 2 of the drawings that the nozzle N is supported in spaced concentric relation to the inner surface of the bushing section 9. As the gasoline enters the tank through the

screen cylinder 14, the displaced air may find free egress from said tank through the perforations of the screen cylinder 14 and the openings 11, and hence outwardly through the open end of the bushing. Thus splashing of the gasoline or other liquid fuel outwardly through the bushing opening due to inadequate provision for the escape of displaced air will be obviated.

From the above description considered in connection with the accompanying drawing, it will be seen that I have devised a very simple construction which permits of the rapid filling of the tank without loss of fuel and with absolute safety. Should a lighted match or other flame be accidentally dropped through the filling bushing while the plug is removed therefrom, it will be caught in the screen cylinder 14, thereby preventing the ignition of the fuel contents of the tank. The device being constructed of simply formed sheet metal parts, it is apparent that the same may be provided as standard equipment on automobile fuel tanks, without appreciable increase in production costs. However, it will be obvious that said device may also be produced in various other sizes and employed in connection with other fuel-containing tanks or receptacles. Likewise, while I have herein disclosed a preferred form of the improved filling bushing and a simple and inexpensive method of providing the same with the nozzle positioning flanges or lugs 12, it is to be understood that this bushing construction is susceptible of more or less variation in the form, construction and relative arrangement of its several parts, and I therefore, reserve the privilege of embodying the essential characteristics of my present disclosure in such other alternative structural forms as may be fairly incorporated within the spirit and scope of the appended claims.

I claim:

1. In combination with a fuel container having an opening in a wall thereof, a filling bushing extending inwardly through said opening and provided on one end with means fixed to the container wall, circumferentially spaced sections of the bushing wall adjacent its other end being projected inwardly to form a plurality of openings and an inwardly projecting lug at one edge of each opening, said lugs adapted to support a fuel supply nozzle in spaced relation to the wall of the bushing to provide a passage therebetween for the free egress of air from the interior of the container through said openings.

2. In combination with a fuel tank having an opening in a wall thereof, a bushing extending inwardly through said opening provided with means on one end attached to the tank wall, the inner end portion of the bushing being of reduced diameter and provided with a plurality of air egress openings in its

wall, and an elongated screen cylinder open at one of its ends to receive the latter end portion of the bushing, said end of the screen cylinder having a flanged reinforcing ring externally secured thereto to abut against a shoulder connecting the inner and outer sections of the bushing, and the wall of the screen cylinder in spaced relation to said ring being provided with means adapted to coact with complementary means on the wall of the bushing to retain said screen cylinder and the bushing in assembled relation.

3. As an improved article of manufacture, a filling bushing for fuel containers provided in the wall thereof with a plurality of circumferentially spaced air egress openings, and an internally projecting lug at one edge of each of the openings adapted to support a fuel supply nozzle in spaced relation to 20 said openings.

4. As an improved article of manufacture, a sheet metal fuel inlet bushing for fuel containers having an internally threaded end section to receive a closure plug, the bushing wall in spaced relation to said threaded section being provided with a plurality of circumferentially spaced openings and an internally projecting lug at one edge of each of said openings adapted to support a fuel 30 supply nozzle in spaced relation to said openings.

5. As an improved article of manufacture, a filling bushing for insertion through an opening in the wall of a fuel container, said bushing having means at one end adapted to be secured to the outer face of the container wall, the other end portion of the bushing being reduced in diameter and provided with a plurality of spaced internally projecting 40 lugs below the upper end of said reduced portion adapted to limit the insertion of a fuel supply nozzle through the bushing and support said nozzle in spaced non-contacting relation to the wall of the reduced portion 45 of the bushing.

6. A filling bushing for fuel tanks comprising a hollow body portion adapted for positioning through the wall of the tank, means for securing the bushing at its outer 50 end to said wall of the tank, said body portion having stamped and inwardly bent lugs projecting from its inner wall adapted to engage a fuel supply nozzle when inserted in the bushing to hold the nozzle out of contact with said inner wall and permit free 55 escape of air from the container during filling.

7. A filling bushing for fuel tanks comprising a hollow body portion adapted to be 60 fitted through the wall of a fuel tank, means for securing the outer end of the body portion to the wall of the tank, said body portion having lugs stamped and struck inwardly from the wall thereof to provide openings through 65 the sides of the bushing near said wall and

to provide inwardly projecting lugs outstanding from the inner wall of the bushing to receive and support a fuel supply nozzle when inserted in the bushing and to hold the nozzle in spaced relation to the wall of the 70 bushing and freely venting the container during filling.

In testimony that I claim the foregoing as my invention, I have signed my name hereto.

RICHARD STRINDBERG.
